UNITED STATES PATENT OFFICE.

WILLIAM H. JACOBS, OF NEW YORK, N. Y., ASSIGNOR, BY MESNE ASSIGNMENTS, TO THE LOCK-TITE ENVELOPE CORPORATION, OF NEW YORK, N. Y., A CORPORATION OF NEW YORK.

WRAPPER OR BINDER.

1,148,487.

Specification of Letters Patent.

Patented July 27, 1915.

Application filed October 17, 1914. Serial No. 867,059.

To all whom it may concern:

Be it known that I, WILLIAM H. JACOBS, a citizen of the United States, residing at New York city, New York, have invented 5 certain new and useful Improvements in Wrappers or Binders, of which the following is a clear, full, and exact description.

This invention relates to improvements in 10 wrappers or binders made of paper or similar flexible material, and adapted particularly for application to books, catalogues, etc. for the purpose of sending them by mail or other purpose.

One of the objects of the invention is to 15 provide a sheet of flexible material with means for adapting the same to be wrapped about a book, catalogue, etc. so that the said sheet may be readily applied thereto.

Other objects of the invention are to provide 20 a simple and efficient wrapper or binder.

These being among the objects of the present invention the same consists of certain features of novelty to be hereinafter 25 described and then claimed with reference to the accompanying drawing illustrating a desirable embodiment of the invention and in which—

Figure 1 is a plan of the preferred blank 30 from which the wrapper or binder is made; Fig. 2 is a perspective view showing the complete wrapper or binder applied to a book; and Fig. 3 is a transverse section on the line 3—3 Fig. 2.

35 A partial disclosure at least of the present invention is contained in my co-pending application filed June 12, 1914, Serial No. 844,619.

The preferred blank for the improved 40 wrapper or binder herein is shown in Fig. 1, and comprises a sheet of flexible material such as paper or the like having between its ends a body comprising substantially rectangular portions 10, 11, separated by a narrower portion 12, while a similar narrower portion 13 is located to one side of the larger portion 10. The larger portions 10, 11 are of substantially the same area and when the complete wrapper is applied to a book, for 45 instance, they will lie against the opposite sides of said book, while the narrower portion 12 will lie opposite the back thereof, with the narrower portion 13 lying opposite the edges of the leaves of the book. At

the outer side of the portion 11 of said 55 sheet there is located an oblong transverse portion 14, 15, of which the parts 14 and 15 are of substantially the same area, and the part 15 is provided with a single pair of transverse slits 16 and 17, which slits are 60 substantially parallel with the continuous side edges of the strip, whereby wing portions 18, 19 are provided which extend transversely of the transverse portion 14, 15, or longitudinally of the sheet. The opposite 65 end 20 of the sheet, beyond the narrow transverse portion 13 is adapted to be formed into a flap, which may be done by cutting off the corners thereof, or as indicated in the drawing the corners 21 and 22 70 may be folded over along the lines 23, 23 so as to produce a tapering flap. The manner of forming a pocket to be engaged by said flap is clearly disclosed in my said application, but a brief description will be here 75 given.

To form the blank into a complete wrapper or binder the part 15 between the slits 18, 19 is pasted over against the part 14, but first within the edge fold thereby produced, 80 a reinforcing tape or some similar flexible material 30 is introduced in the fold, as fully described in my said application. Next, the ends of the part 14 and the wing 85 extensions 18, 19 are pasted against the adjacent surface of the body of the sheet of flexible material so that part 15 is turned underneath part 14. The paste should not of course extend to a point between the slits 16, 17. In this way a pocket will be formed 90 located on one surface of said sheet, preferably having a reinforced edge.

In applying the wrapper or binder to a book, catalogue or the like, the intermediate narrow transverse portion 12 is secured to 95 the back of said book such as 25 (see Figs. 2 and 3) as by paste applied at points 26, 27 indicated in Fig. 1. Of course some other suitable means for attaching the sheet to the back of the book may be substituted. Preferably, the narrow transverse portion 12 is defined by parallel lines 28, 29 which may be printed, scored or indented upon the surface of said sheet opposite to that on which the pocket is located, whereby to guide one in 100 properly securing the wrapper or binder in position. The location of the point of attachment at 12 will of course be determined 105

by the proportions of the wrapper or binder. Having secured the wrapper or binder to the book, etc., the portions 10, 11 are caused to engage over the opposite sides of the book, 5 while the narrower portion 15 is brought around the free edges of the leaves, and the end of the flap 20 is tucked into the pocket 24.

What I claim as new is:

1. A wrapper or binder, comprising a 10 flexible sheet having continuous substantially parallel edges, and provided at one end with a transverse portion having a turned under part and secured at the ends to one face of said sheet, to provide a pocket, 15 said turned-under part extending from the inner edge of said transverse portion toward the adjacent end of the article so as to provide an edge-fold located at that edge of said transverse portion which is remote from 20 said end of the article, and a flexible reinforce in the edge fold between said transverse portion and turned under part, the other end of said sheet constituting a flap to engage said pocket.

2. A wrapper or binder, comprising a 25 flexible sheet having continuous substantially parallel edges, and provided at one end with a transverse portion having a turned under part and secured at the ends to one face of said sheet, to provide a pocket, said ends of said transverse portion having wings which extend transversely of said transverse portion and are secured along the side edges of said sheet, and a flexible reinforce in the edge fold between said transverse portion and turned under part, the

other end of said sheet constituting a flap to engage said pocket.

3. A wrapper or binder, comprising a 40 flexible sheet free from extensions at its side edges, so as to have continuous substantially parallel edges, and provided at one end with a transverse portion secured at the ends of one surface directly to one face of said sheet to provide a pocket, said surface being continuous with said face, the other end of said sheet constituting a flap to engage said pocket, said sheet being adapted to be laid out flat, with said pocket disposed at one end thereof.

4. A wrapper or binder, comprising a 45 flexible sheet free from extensions at its side edges, so as to have continuous substantially parallel edges, and provided at one end with a transverse portion secured at the ends to 50 one face of said sheet to provide a pocket, said ends of said transverse portion having wings which extend transversely of said transverse portion and are secured along the side edges of said sheet, the outer edges of 55 said wings constituting edges separate from those edge portions of said sheet to which said edges are secured, although continuations of said edges, and the other end of said sheet constituting a flap to engage said 60 pocket.

Signed at New York city, New York, this 15th day of October, 1914.

WILLIAM H. JACOBS.
